4 Claims. (Cl. 48—197)

1

The present invention relates to the handling of liquids having a relatively high vapor pressure under the conditions obtaining.

An example of such handling is the transportation through pipes exposed to atmospheric conditions of liquid phase material normally gaseous under such conditions.

For purposes of illustration, the invention will be particularly described in connection with its application to the piping and utilization of liquefied normally gaseous hydrocarbons such as propane and butane, which are frequently employed as raw materials in the manufacture of combustible gas.

One of the uses of such liquefied normally gaseous hydrocarbon material in the manufacture of combustible gas, is in the supplementing, during periods of peak loads, of the carburetted water gas normally produced in carburetted water gas sets from solid fuel and heavier hydrocarbon oils.

Such utilization of liquefied normally gaseous hydrocarbons frequently includes the cracking of these materials by passage through the fuel bed of the water gas generator in a step commonly termed "reforming," and may also include a step of utilizing these materials for enrichment without material cracking.

It is economical from the standpoint of the investment costs to store hydrocarbon materials such as propane and butane as liquids under relatively elevated pressure because of the greatly reduced size of the storage equipment required to store these materials in gaseous form. It is also economical from the standpoint of investment to transport these materials in liquid form, from storage to a point adjacent the gas apparatus in which they are to be utilized, because of the greatly reduced size of pipe required as compared with that required to transport them as gases.

Such liquid storage is customarily exposed to existing atmospheric temperature conditions and therefore the storage of the liquid usually occurs under a very considerable pressure due to this temperature. For example, in the case of commercial liquid propane, at say 30° F. the vapor pressure will be of the order of 100 pounds per square inch absolute, while at 72° F. the vapor pressure will be of the order of 160 pounds per square inch absolute. Since the liquid in storage is in equilibrium under the existing storage pressure and the existing atmospheric temperature, any pressure differential causing a flow of the liquid from storage will cause the evapo-

2

ration of a portion thereof. As a result, the material passing through the pipe leading from the storage vessel toward the point of utilization is a varying mixture of liquefied propane and propane vapor, small differences in percentage of evaporation by weight resulting in great differences in the proportion of vapor present by volume. Such a mixture cannot be accurately metered by presently available liquid or vapor meters, with the result that the rate of utilization of the material may not be accurately known or ascertained.

One of the objects of the present invention is to provide a method of and apparatus for the delivery through pipes of liquid material of relatively high volatility under the ambient conditions, in the use of which the liquid material delivered to a zone of utilization, treatment, or other disposal may be accurately metered in spite of the formation of vapor phase occurring as a necessary incident to a drop in pressure in the transportation system. Other objects of the invention will appear as the specification proceeds.

For convenience, the invention will be more particularly described in connection with the piping of liquefied propane from storage under pressure to utilization in the manufacture of carburetted water gas, and in connection with the description of the figures, which form a part of this specification, and in which

Figure 1 shows, somewhat diagrammatically, partly in elevation and partly in vertical section, a carburetted water gas set supplied with and utilizing liquefied propane in accordance with a form of the present invention chosen for illustration;

Figure 2 shows, somewhat diagrammatically, partly in elevation and partly in vertical section, another form of the apparatus of the invention; and

Figure 3 shows a portion of the apparatus of Figure 2 with modifications.

Referring to Figure 1:

1 generally indicates the generator, 2 the carburetter, 3 the superheater and 4 the wash box of a carburetted water gas set.

The generator is provided with an ignited fuel bed 5, of solid fuel, such as coke, resting on a grate (not shown). The generator is further provided with air supply means and steam supply means 6 and 7 respectively for upwardly air blasting and steaming the fuel bed. The generator is also illustrated as provided with secondary air supply means 8 and oil supply means

9 arranged to spray oil onto the top of the fuel bed.

The generator is further illustrated as provided with a gas take-off connection 10, leading from its upper portion to the upper portion of the carburetter 2, and with the gas take-off 11, provided with valve 11a, and leading from its lower portion below the grate to the wash box 4.

The carburetter is illustrated as devoid of checker-brick, but provided with the refractory lining 12. 13 indicates an oil supply means arranged to spray oil into the carburetter. The base of the carburetter is illustrated as connected with the base of the superheater by the connection 14.

The superheater is illustrated as provided with refractory checker-brick 15, stack valve 16, and gas take-off 17, provided with valve 17a, and leading from the upper portion of the superheater to the wash box 4. The superheater is further illustrated as provided with steam supply 18 for "back-running."

In Fig. 1, the operating connection indicated between valves 11a and 17a is intended to be diagrammatic, the connection being such that the opening or closing respectively of one valve by the hydraulic cylinder 17b is accompanied by the closing or opening respectively of the other.

The wash box 4 is illustrated as provided with the sealing liquid supply 19 and the liquid overflow 20, which are adapted to provide a liquid seal for dip-pipe 21, which is connected with the pipes 11 and 17 leading from the generator base and superheater top respectively. The valved gas take-off 22, provided with valve 22a, leads from the wash box to the gas take-off main 23, which leads to storage, condensing and purification apparatus (not shown).

25 generally indicates a pressure storage tank for liquefied propane, which is to be supplied in metered quantities to the carburetted water gas set as desired.

In accordance with the form of the invention chosen for illustration, liquefied propane is caused to flow from the storage tank 25, through pipe 26 to a phase separating vessel 27 in response to a pressure differential therebetween. If desired, pipe 26 may be provided with either the hand operated throttling valve 28, or the automatically operated reducing valve 29, or both.

The function of the phase separating chamber 27 is to cause the separation from each other of liquefied propane passed from storage through pipe 26 and propane vapor produced in transit by evaporation incidental to the drop in pressure through pipe 26 including valves 28 and 29, if provided. The material flows into chamber 27 in a chilled condition due to this evaporation. Propane vapor separated in chamber 27 passes by way of pipe 30, provided with valve 31, to the gas take-off main 23, and is illustrated as metered en route by the vapor meter 32.

Liquid propane separated in chamber 27 is delivered by pump 33 by way of pipes 34 and 35 to the water gas set, passing through the liquid header 36, which may supply a plurality of gas sets, and through pipe 37 to the particular water gas set shown, entering the top of the superheater 3, with the "back-run" steam, supplied through 18.

Pipe 37 may be provided with the regulating valve 38, for regulating the flow of liquid propane to the set and with the hydraulic operating valve 39 for controlling the admission of liquid propane

thereto during the desired periods of a cycle, for example, as controlled by the usual automatic controlled machine.

5 Liquid meter 40 is arranged in pipe 37 for metering the liquid propane flowing therethrough to the gas set. 41 is a shut-off valve, the closing of which disconnects pipe 37 from the liquid header 36.

The phase separating vessel 27 is illustrated as provided with the float chamber 42 and with the float 43, which is operably connected with the valve 31 in the vapor line from the phase separating vessel in such manner that should the float 43 sink, due to a lowering of the level of the liquid propane in chamber 27, the valve 31 will be moved toward the wide-open position, thereby increasing the flow of vapor from chamber 27, through pipe 30, to the gas take-off main 23. Vice versa, should float 43 rise because of the rising of the level of the liquid propane in chamber 27, valve 31 will be moved toward the closed position, thereby reducing the flow of vapor through pipe 30.

25 The automatic reducing valve 29, which may or may not be provided as desired, is illustrated as operably connected, as by pipe 44, with chamber 27, in such manner as to be responsive to changes of pressure within the chamber, increasing pressure in chamber 27 tending to move valve 29 toward the closed position and decreasing pressure in chamber 27 tending to move valve 29 toward the wide-open position.

30 The following is given as an illustrative example of the operation of the form of the apparatus of the invention chosen for illustration in Figure 1, bearing in mind that its use in connection with the handling of propane specifically and its use in connection with the specific utilization of the conveyed liquid in a carburetted water gas set are purely for purposes of illustration. The invention, in its broader aspects, is not limited to the conveying of any particular liquid of the general character described nor to any particular utilization, treatment or other disposal of the liquid delivered.

35 The ignited fuel bed 5 in generator 1 is alternately blasted with air and steam in a cyclic operation.

40 During the air blasting step of the cycle, termed the "blow," with valve 11a closed and the stack valve 16 open, air blast admitted through air supply means 6 raises the fuel bed to a high temperature and stores heat therein. The resulting producer gas issuing from the top of the fuel bed is burned with secondary air admitted through air supply 8. The burning producer gas and the resulting products of combustion traverse the carburetter and superheater, storing heat in the refractory linings and checker-brick thereof and issue to the atmosphere through the stack valve 16.

45 After the fuel bed and the carburetter and superheater have been raised to the desired temperatures, the "blow" is terminated, and the water gas generating period termed the "run" is begun. With valve 11a remaining closed, steam is admitted to the base of the generator through steam supply 7, for reaction with the ignited fuel bed to produce water gas. The resulting "up-run" water gas passes from the top of the fuel bed through connection 10 to the carburetter, thence through connection 14 to the superheater. The stack valve 16 is closed shortly after the beginning of the steaming operation, that is, after the "up-run" water gas has purged through the

stack, the combustion products of the air blast remaining in the set at the end of the air blasting operation. After this purge with valve 17a in pipe 17 open, the "up-run" gas passes through pipes 17 and 21 to wash box 4 and thence through take-off 22 and valve 22a to take-off main 23.

During the "up-run," the blue water gas passing through the carburetter and superheater is carburetted with oil gas produced by spraying oil into the top of the generator through oil supply 9 and/or into the top of the carburetter through oil supply 13, the heat stored during the "blow" serving to vaporize the oil and to crack the resulting oil vapors in the presence of the blue water gas and excess steam from the generator.

After the "up-run," the admission of steam through supply 7 is ceased and the valves 11a and 17a are reversed. Steam is admitted through steam supply 18 and passed reversely through the superheater, carburetter and generator, and the resulting "back-run" water gas passed to the wash box by way of pipe 11 from the base of the generator and thence by way of connection 22 to the gas take-off main 23.

After the termination of the "back-run," the valves 11a and 17a are again reversed, and a short "up-run" is made with steam supplied to the base of the generator through steam supply 7.

Following this "up-run," the cycle is repeated, by the initiation of another air blasting operation, the stack valve 16 not being opened until the products of combustion have pushed the carburetted water gas, remaining in the set at the end of the run, out of the set through connection 11.

The foregoing description of the operation of a carburetted water gas set was chosen purely for illustration and may be widely varied.

For the purpose of conveniently increasing the output of a carburetted water gas set during periods of peak loads, it has been proposed to supplement the gas production, from solid fuel and from the conventional enriching oils, with gas produced by the vaporization and/or the vaporization and pyrolysis of liquefied normally gaseous hydrocarbons such as propane and butane.

In the embodiment of the present invention illustrated in Figure 1, during the "back-run," liquid propane is pumped from the phase separating chamber 27 by pump 33 through pipe 35, liquid header 36, liquid meter 40 and pipe 37 into connection 17 in the proximity of the superheater top, to which the steam is simultaneously admitted through steam supply 23. The resulting propane vapor passes reversely through the superheater and carburetter and into the generator fuel bed with the "back-run" steam. In its passage through the fuel bed with the steam, propane vapor is cracked, reacted, or "reformed" simultaneously with the production of water gas in the fuel bed by reaction of the steam therewith, the mixed gases comprising water gas, excess steam and gas resulting from the pyrolysis of the propane vapor, pass through the "back-run" pipe 11 to the wash box 4 and thence to the gas take-off main 23.

Simultaneously the vapor phase propane separated in the phase separating chamber 27 may be passed by way of pipe 30, valve 31, and the vapor meter 32 into the gas take-off main 23, serving as "cold enrichment" of the gas produced in the set.

At the end of the "back-run," the carburetter and superheater are full of propane vapor resulting from the evaporation of the liquid propane admitted through pipe 37 and which has not been

cracked by passage through the fuel bed. This vapor phase propane is pushed through the wash box into the gas take-off main by the succeeding "up-run" gas, and also serves as enrichment.

According to the embodiment of the invention illustrated in Figure 1, the mixture of liquid and vapor phase propane, produced by the evaporation due to drop in pressure as the liquid propane flows from storage tank 25, is separated into the respective liquid and vapor phases in chamber 27. The separated liquid phase is pumped by pump 33 through the liquid meter 40 under a sufficiently elevated pressure so that when the liquid propane passes through the liquid meter 15 the temperature of the propane is below its boiling point under said elevated pressure.

In case the liquid phase material is a mixture, the pressure at the liquid meter is preferably such that the temperature obtaining is below the boiling point of the lowest boiling constituent thereof.

The pressure is preferably such as to preclude the presence of any substantial proportion, by volume, of vapor phase with the separated liquid material as it passes through said liquid meter, in spite of any pressure drop or rise of temperature which may occur between the pump and the liquid meter.

Since the evaporation of a portion of the liquid propane due to pressure drop in the passage from the storage tank to the phase separating chamber abstracts heat from the remaining liquid phase material reducing its temperature, the pressure developed by pump 33, therefore, need only be sufficient to maintain the chilled liquid in the liquid phase up to and through the liquid meter as described.

In the apparatus illustrated in Figure 1, connection 26 leading from the storage tank to the phase separator is shown provided with a hand operated throttling valve and with an automatically operated reducing valve. Either or both of these valves may be omitted if desired. The hand operated throttling valve may be desired to produce a selected pressure drop in line 26, and the automatically operated reducing valve may be desired to maintain a constant pressure drop therein.

As stated, however, either or both of these valves may be omitted. In the absence of reducing valve 29 and its operating connection 44, any lowering of the level of the liquid in chamber 27 moves valve 31 toward the wide-open position, and by bleeding vapor from chamber 27 reduces the pressure therein, which in turn increases the differential pressure between the storage tank and the chamber 27, thereby increasing the flow of material through line 26 to restore the liquid level in chamber 27. Any increase in the height of the liquid level in chamber 27 is accompanied by the reverse operation of the float 43 and valve 31, which increases the pressure in chamber 27, which in turn reduces the pressure differential between tank 25 and chamber 27, thereby reducing the flow through line 26 to restore the liquid level in the chamber.

By proper selection of pressure conditions in chamber 27, with respect to other conditions obtaining, including the supplying of heat to the liquid from the atmosphere or otherwise, if required, any desired proportion of the material passed from storage may be evaporated and bled off from the chamber as vapor through connection 30. The proportion of vapor phase thus formed and separated may preferably be a minor

portion of the material leaving storage, but if desired the major portion may be thus separated as vapor phase material, a minor portion being passed as liquid through the liquid meter. With commercial liquid propane, up to approximately 50% of the liquid may be evaporated by expansion down to atmospheric pressure without requiring the supply of extraneous heat. Since with the evaporation of any considerable proportion of the liquid, the temperature of the remaining liquid will be reduced well below the ambient temperature, heat for further evaporation may be conveniently supplied from the atmosphere.

In many cases, such as in the use of the invention particularly described, after the separated liquid phase material has been metered there is no need to inhibit the vaporization thereof. In the use of liquefied normally gaseous hydrocarbons, such as hydrocarbons of from 3 to 4 carbon atoms per molecule, in the manufacture of combustible gas the liquefied hydrocarbon material is to be vaporized in the process in any event.

The invention usefully employs the evaporation of a portion of the liquefied hydrocarbon material to permit the conveying of the remainder in liquid phase to the proximity of the zone of its utilization and its accurate metering.

The vapor phase material separated in chamber 27, may also be accurately metered prior to use. If desired, baffles or other phase contacting means, such for example as fractionating column packing, may be employed if desired to remove entrained liquid phase material from the separated vapor phase prior to the metering of the latter.

As a specific example of the operation of the invention, liquefied propane in a storage tank under a temperature of about 30° F. and under a pressure of about 100 pounds per square inch absolute pressure and having an enthalpy of about 123 B. t. u. per pound is passed through a line 4 inches in diameter to a phase separating chamber with a pressure drop en route of about 40 pounds per square inch, with an evaporation of about 10% of the material and a drop in temperature to about 1° F.

The separated vapor phase material is bled off to the gas take-off main serving six carburetted water gas sets.

The separated liquid phase material is pumped by a booster pump under an increase in pressure of about 50 pounds per square inch through a 4 inch line about 200 ft. long and thence through six 2 inch lines about 100 ft. long to six liquid meters, under ambient temperature conditions of about 120° F., the metered material going to the six 9.0 ft. diameter water gas sets during the "back-run" period of the cycle of each set.

Approximately 70 gallons of propane per cycle is supplied to each of the six sets with about 10 cycles per hour. About 65% of the propane supplied is "reformed" by passage through the fuel beds of the generators of the respective sets, being supplied thereto during the "back-run" with the "back-run" steam to the superheater tops of the several sets. About 35% of the propane is used as "enrichment" not being reformed, including propane vapor remaining in the generator top, carburettor and superheater at the end of the "back-run" as well as the separated vapor phase material bled into the gas take-off main.

Under the increased pressure supplied by the booster pump, the ambient temperature at the liquid meter is well below the boiling point of

the liquid propane being metered, and no substantial volume of vapor phase material is present to impair the accuracy of the metering operation.

In the employment of the invention in connection with the operation of a considerable number of carburetted water gas sets, due to staggering of the cycles of the individual gas sets, pump 33 may be continuously pumping separated liquid phase hydrocarbon material from the separator 27 to the liquid header 36, the liquid flowing therefrom continuously through at least one liquid meter. In a case in which the invention is employed in connection with the operation of only one carburetted water gas set, the flow of liquid hydrocarbon material from the phase separator 27 through the liquid meter will normally be discontinuous, the flow taking place during only a certain period or periods in the gas-making cycle. In such case, the refrigeration and the repressuring of the separated liquid phase material should preferably be such as to maintain the material in the line from the pump to and through the liquid meter in liquid phase during the period or periods of the cycle in which there is no flow of material through line 35. In using the invention in connection with the operation of only a few water gas sets, the flow of liquid material from pump 33 may likewise be discontinuous, although not to such an extent as in the case of the operation of only one gas set and therefore the same considerations may apply but to a lesser degree.

Referring to Figure 2:

This figure illustrates another form of the invention. Pipe 100 leads from a storage tank (not shown), which may be similar to tank 25 in Figure 1, containing liquid propane, under the pressure resulting from storage under atmospheric temperature conditions.

The liquid propane passes through pipe 100 to the heat exchanger 101 in response to pressure differential therebetween.

The heat exchanger is illustrated as provided with upper and lower tube sheets 102 and 103 respectively and with the tubes 104 extending therebetween.

The liquid propane containing some vapor, produced due to pressure drop in pipe 100, enters the heat exchanger by way of the space above the upper tube sheet and flows downwardly through the tubes and thence by way of the space below the lower tube sheet, the connection 105, liquid meter 106, and connection 107, to a carburetted water gas set (not shown). For example, the utilization of the liquid propane in the gas manufacturing apparatus may be as shown and described in connection with Figure 1.

The flow of the liquid propane from storage to the gas set is illustrated as controlled by valve 108 in line 107, which valve may be conveniently operated by the hydraulic cylinder 109, for example, in response to the command of the automatic control machine (not shown) of the water gas set, the quantity being regulated by the adjustment of valve 108a.

A portion of the liquid propane leaving storage through pipe 100, is bled off through expansion valve 110, the resulting chilled vapor, passing into the lower portion of the space between the tube sheets of heat exchanger 101, and back and forth between baffles such as 110a, cools the mixture of liquid propane and propane vapor passed into the heat exchanger above the upper tube sheet. This results in the condensation

of the propane vapor in said mixture and ensures the passage of substantially only liquid propane through the liquid meter 106. Valve 110 is provided with means for adjusting its opening, and in operation sufficient liquid propane is expanded therethrough, to reduce the temperature of the liquid propane issuing from the base of the heat exchanger, sufficiently low as to ensure the absence of any substantial volume of vapor phase therein during metering.

The propane vapor bled off through expansion valve 110, passes out of the heat exchanger by way of connection 111, and is passed through the vapor meter 112, from whence it passes, by way of connection 113, to the gas take-off main 114, which may be connected to one or more gas sets (not shown) in similar manner to take-off main 23 in Figure 1.

Expansion valve 110 is illustrated as operated by hydraulic cylinder 115, which may be actuated by the automatic control machine (not shown) of the carburetted water gas set, so as to be moved toward the wide-open position simultaneously with the opening of valve 108, in line 107.

If desired, the operation of valve 110 may be arranged so that it does not entirely close, thereby bleeding off through the valve a small proportion of propane, to provide refrigeration in the heat exchanger during periods of the water gas cycle when valve 108 is closed. To reduce loss of refrigeration the heat exchanger is illustrated as lagged with the heat insulating material 116.

In the form of the invention illustrated in Figure 2, the vaporization of an additional proportion of the liquid propane permits the omission of the step of repressuring the liquid propane prior to passage through the liquid meter. If the additional vapor cannot be conveniently utilized, as for cold enrichment as described, any desired proportion of the vapor leaving the heat exchanger may be compressed, after cooled and returned to storage as liquid. The same procedure may be followed, if desired, in the case of any proportion of the separated vapor phase material from the phase separator of Figure 1.

Referring to Figure 3:

Figure 3 shows the upper portion of the apparatus of Figure 2, modified somewhat to provide for the periodic removal of uncondensed gas from the upper portion of the heat exchanger should such gas tend to accumulate.

As in Figure 2, 100 indicates the pipe leading from the liquid propane storage. 101 is the heat exchanger generally. 102 is the upper tube sheet, 104 the tubes, 110a a baffle, and 116 the insulating lagging of the heat exchanger. 111 is the vapor line leading through vapor meter 112 and connection 113 to utilization of the vapor, such as by admission to the gas take-off main (not shown).

In the modified apparatus of Figure 3, a bleeder connection 120 is provided leading from the upper portion of the space above the upper tube sheet to connection 111. The bleeder connection is illustrated as provided with two valves 121 and 122 arranged in series.

Pressure actuated valve 121 is operatively connected by way of pipes 120 and 123 with the space above the upper tube sheet and is arranged to remain closed when the pressure in said space is below a predetermined value, and to open when said pressure is above said predetermined value. Valve 122 is operatively con-

nected with float 124, in such manner that when the float is maintained in its uppermost position by the liquid in the space above the tube sheet, the valve 122 is in the closed position, but when a lower level of liquid causes a falling of the float, valve 122 is moved toward the open position.

As a result of these provisions, if a sufficient body of uncondensed gas accumulates in the top of the heat exchanger, under the storage pressure less the line drop, both valves will be opened and the gas automatically bled off. The refilling of the space above the upper tube sheet with liquid raises the float and closes valve 122. Due to provision of valve 121 pressure in the top of the heat exchanger will not be unduly reduced with the consequent flashing-off of unnecessary proportions of the liquid.

As previously stated, the invention is capable of many other applications than the specific application particularly described above. It may readily find use in the handling and utilization of other normally gaseous hydrocarbons than propane and butane, such for example as ethane, ethylene, propylene, butylenes and others. Moreover, it may be applied to the handling of volatile liquids, other than hydrocarbons, such for example as methyl chloride, boiling point -24° C., methyl amine, boiling point -6.7° C., vinyl chloride, boiling point -12° C. and others. The invention is not limited to use with organic liquids as it may be readily applied to the handling of such materials as liquid anhydrous ammonia, boiling point -33° C. and to superheated water.

The invention is applicable to the piping and metering of liquid phase material containing two or more constituents, one or more of which may tend to separate as vapor phase from the remaining liquid material upon drop in pressure under the ambient temperature conditions. Included is liquid phase material relatively non-volatile at atmospheric pressure under the temperature conditions obtaining and containing dissolved material which is gaseous at atmospheric pressure under the temperature conditions obtaining and maintained in liquid phase by elevated pressure. Such liquid phase materials include, for example, aqueous ammonia and carbonated liquids.

The invention has particular advantages in its utilization of liquefied normally gaseous hydrocarbon material in the manufacture of combustible gas, for example, in a carburetted water gas set, as previously described and otherwise. In such use, separated vapor phase material bled off from the phase separating chamber may be very conveniently employed in the gas-making operation, as well as the separated liquid material. This vapor phase material may be bled into the gas take-off main, as previously described, at any period in the cyclic operation of any gas set connected therewith, or may be passed into any set during any desired gas-making period, for purposes of enrichment with little or no cracking or to be "reformed" by passage through the fuel bed, with cracking therein to lighter hydrocarbon material, hydrogen, and carbon.

In the claims the expressions "substantial volume of vapor phase material," "substantial volume of vapor phase hydrocarbon material" and similar expressions are intended to mean volumes of vapor such as to affect the accuracy of metering of the liquid phase material beyond the limits of reasonable tolerance. It is obvious that from this standpoint the lower the proportion

of vapor phase in the material passing through the liquid meter the better. It is likewise obvious that the tolerances as to meter accuracy may vary widely as between different uses of the invention. Preferably the proportion of vapor phase accompanying the liquid phase material when metered should be less than 5% thereof by volume, more preferably should be less than 3% thereof, and still more preferably less than 2% or even 1% thereof. In the case of normally gaseous hydrocarbons these proportions represent the evaporation of extremely small proportions by weight. The invention, however, is not necessarily limited to the presence of any particular proportion of vapor phase material with the liquid phase undergoing metering.

Other modifications may readily occur to those skilled in the art without departing from the spirit of the present invention, which is intended to be limited only as required by the appended claims and the prior art.

We claim:

1. The method of distributing normally gaseous hydrocarbon material employed in the manufacture of combustible gas by a process involving alternate heating of contact material in a gas-generating set and passing hydrocarbon and steam therethrough in a cyclic operation, comprising flowing said liquefied normally gaseous hydrocarbon material from a container in which pressure conditions are such as to maintain said normally gaseous material substantially in the liquid phase therein under the temperature conditions obtaining, along a confined path in which pressure conditions are reduced with respect to said container to cause flow from said container and to cause partial conversion of said liquefied normally gaseous hydrocarbon material to the vapor phase with the chilling of the remaining liquid phase material, to a confined phase separating zone; withdrawing vapor phase material; flowing said chilled liquefied normally gaseous hydrocarbon material from said phase separating zone along a second confined path to and through a liquid meter at an increased pressure with respect to said phase separating zone such that the temperature of said chilled liquefied normally gaseous hydrocarbon material in said second confined path is below its boiling point therein; thereafter passing said metered hydrocarbon material with steam through said hot contact material of said gas-generating set to produce combustible gas.

2. The method of utilizing normally gaseous hydrocarbon material employed in the manufacture of combustible gas by a process involving the alternate heating of contact material in a gas-making apparatus and passing normally gaseous hydrocarbon and steam therethrough in a cyclic operation and the enriching of the gas produced during a gas-making period of the cycle with normally gaseous hydrocarbon material, said normally gaseous hydrocarbon being stored in a container in which pressure conditions are such as to maintain said normally gaseous hydrocarbon substantially in the liquid state therein under the temperature conditions obtaining, which comprises conducting said liquefied normally gaseous hydrocarbon along a confined path in which the pressure conditions are reduced with respect to said container to cause flow from said container and to cause partial conversion of said liquefied normally gaseous hydrocarbon material to the vapor phase with the chilling of the remaining liquefied normally gaseous hydrocarbon

material, to a confined phase separating zone; withdrawing and metering the resulting separated vapor phase hydrocarbon material so as to maintain approximately constant liquid level in said phase separating zone; flowing said chilled liquefied normally gaseous hydrocarbon material from said phase separating zone along a second confined path to and through a liquid meter at an increased pressure with respect to said phase separating zone such that the temperature of said chilled liquefied normally gaseous material in said second confined path is below its boiling point therein; thereafter passing said hydrocarbon material which was metered in liquid phase through said heated contact material in the presence of steam during a gas-making period of said cycle, and mixing with combustible gas thereby produced said vapor phase hydrocarbon material which was separately metered in vapor phase.

3. An apparatus for distributing liquefied normally gaseous hydrocarbon material in the manufacture of combustible gas in a gas-making set, including a gas-making generator adapted to contain hot contact material, said liquefied normally gaseous material subjected, during distribution, to pressure and temperature conditions which cause partial gasification thereof, comprising a pressure storage tank, a conduit leading from said tank to a confined phase separating chamber, a pressure reducing valve in said conduit responsive to pressure in said phase separating chamber and adapted to close said conduit when the pressure in said phase separating chamber exceeds a predetermined pressure, a second conduit connected to the upper part of said chamber for leading vapor phase material therefrom, a float adapted to rise and fall with the level of the liquid in said phase separating chamber and operatively connected with the valve in said second conduit whereby said valve is moved toward the closed position upon the rise of said liquid level and toward the open position upon the fall of said liquid level, a third conduit connected to the lower part of said phase separating chamber and in fluid flow communication with said gas-making generator, said third conduit having a pump and a liquid meter therein, said pump being located between said phase separating chamber and said meter.

4. An apparatus for distributing liquefied normally gaseous hydrocarbon material in the manufacture of combustible gas in a gas-making set, including a gas-making generator adapted to contain hot contact material, and gas take-off means leading to a gas storage vessel, said liquefied normally gaseous material subjected, during distribution, to pressure and temperature conditions which cause partial gasification thereof, comprising a pressure storage tank, a conduit leading from said tank to a confined phase separating chamber, a pressure reducing valve in said conduit responsive to pressure in said phase separating chamber and adapted to close said conduit when the pressure in said phase separating chamber exceeds a predetermined pressure, a second conduit connected to the upper part of said chamber for leading vapor phase material therefrom and in fluid flow communication with said gas take-off means, a vapor meter located in said second conduit, a float adapted to rise and fall with the level of the liquid in said phase separating chamber and operatively connected with the valve in said second conduit whereby said valve is moved toward the closed position

upon the rise of said liquid level and toward the open position upon the fall of said liquid level, a third conduit connected to the lower part of said phase separating chamber and in fluid flow communication with said gas-making generator, said third conduit having a pump and a liquid meter therein said pump being located between said phase separating chamber and said meter.

JOHN S. HAUG.
